UNITED STATES PATENT OFFICE.

JOSEPH A. HALLS, OF YOUNGSTOWN, OHIO, ASSIGNOR TO THE TRUSCON STEEL COMPANY, OF YOUNGSTOWN, OHIO, A CORPORATION OF MICHIGAN.

ROTARY MACHINE FOR EXPANDING METAL SHEETS.

Application filed November 11, 1925. Serial No. 68,440.

This invention relates to a machine of the rotary type for expanding pre-slitted metal sheets, and has particular reference to certain novel improvements in the type of machine covered by the U. S. Patent of Melvin S. Groh, No. 1,527,403, dated February 24, 1925, and the U. S. application of Melvin S. Groh and Joseph A. Halls, Serial No. 731,634, filed August 12, 1924.

10 A primary object of the invention is to so construct a rotary machine of the type referred to as to increase its utility, and to widen its use, more particularly adapting it for opening and expanding a metal sheet 15 which has been previously slitted in a manner to form the well known "herringbone" type of metal lath. To that end the invention contemplates associating with the ribbed expanding drum a novel means of holding 20 and feeding a slitted sheet of the "herringbone" type whereby the herringbone mesh will be opened evenly and without buckling and without imposing excessive strains on the individual strands at the sides of the 25 slits. Also, in that connection the improvements are so designed and correlated as to permit the sheet to vibrate longitudinally of the expanding drum to adapt itself to the swinging of the strands as they are pulled 30 open to the diagonal positions which they occupy in the finished herringbone lath.

While the invention is necessarily susceptible of structural modification without departing from the principle or scope thereof, a preferred and practical working embodiment thereof is shown in the accompanying drawings, in which:

Figure 1 is a vertical sectional view of a rotary expanding machine embodying the 40 improvements constituting the present invention.

Figure 2 is an enlarged detail sectional view of the sheet holding and feeding unit.

Figure 3 is a top plan view of the said 45 unit in its relation to the feed table of the machine.

Figure 4 is a detail view of an end portion of the machine to show more clearly the end mounting of the pivotal pressure bar.

50 Figure 5 is an elevation of the end portion of the machine shown in Fig. 4.

Figure 6 is a detail top plan view of the end portion of the machine shown in Figs. 4 and 5.

Figure 7 is an elevation of the power end 55 of the machine giving an example of the preferable way of intermittently operating the expanding drum.

Figure 8 is a detail plan view of a pre-slitted herringbone blank indicating by dotted lines its first position with relation to the expanding roll of the machine.

Figure 9 is a plan view of the herringbone sheet partly open.

The machine includes in its general organization a machine frame or stand designated generally by the letter A provided at the top thereof with a horizontal feed table B having at its inner edge an angular mortise b forming a receiving recess for the stationary die block C, and above this die block is arranged a pressure bar D mounted between the angular upstanding supporting brackets E surmounting and mounted upon the frame at the ends thereof and 70 over the feed table portion B. At one side of and adjacent the stationary die or die block C is mounted for rotation a ribbed or shouldered expanding drum designated generally by the reference letter F.

In carrying forward the present invention the rotary expanding drum F is preferably provided with a tool steel or equivalent peripheral shell 1 in which are cut the longitudinally extending die ribs 2. 85 These die ribs are cut sufficiently deep, and are spaced a sufficient distance apart, so as to be adapted particularly for engaging and opening a slitted sheet of the herringbone type, and a necessary and important feature 90 in the construction of the drum is that the die ribs thereof extend continuously in straight lines longitudinally of the drum body, and from end to end thereof, so that each individual rib of the drum will present a substantially continuous flat shoulder that engages throughout the successive uncut strips or vertebra between the rows of diagonal slits in the herringbone blank, thus 95 providing for opening an entire row of said slits at once, producing the herringbone effect in the mesh of the product.

Furthermore, it will be observed that the die ribs 2 are cut upon the steel shell of the drum in sawtooth formation, and cover the entire periphery of the drum body excepting at one point in its circumference where the said ribs are preferably interrupted as at 3 producing at that point a land or wide blank space. This land or blank space is intended, when the roll is at rest in its starting position, to receive the inner edge of the pre-slotted blank as indicated by the dotted lines in Fig. 8 of the drawings thereby to position the uncut edge strip of the blank for engagement by the first rib of the expanding drum 15 when the rotation of the latter is started.

Any suitable gearing appliances may be employed for intermittently rotating the expanding roll, one revolution at a time, that is, providing for its continuous rotation 20 through one revolution to expand a slotted metal sheet of a given length and width, the automatic stopping of its motion when thus revolved one revolution, and then starting the same to take up the expansion of the 25 second sheet. However, for illustrative purposes there is shown in the drawings one way of doing that. In such illustration the expanding drum shaft is shown fitted with the spur gear 4 meshing with an intermediate 30 gear unit 5, interposed between the same and a driving pinion 6 on the drive shaft 7 which carries the belt or power pulleys 8. Associated with these instrumentalities is a clutch-device 9 having a trip lever 10 carrying 35 a trip element 11 adapted to be engaged by a trip detent α on the spur gear 4. The said detent, at the completion of one revolution of the expanding drum engages the trip element 11 of the lever 10, causing the latter 40 to move in a direction to disengage the clutch, thereby automatically stopping the rotation of the drum. When another slotted sheet is inserted, and its inside edge entered into the land 3 of the expanding drum, the 45 machine is again started by manipulating the starting lever 12 having an operating connection 13 with the clutch 9 so as to provide for re-engaging the clutch. This operation is repeated while the machine is at 50 work.

An important and distinguishing feature of the present invention is a sheet holding and feeding unit shown in detail in Figs. 1 and 2 of the drawings. This unit includes 55 a sliding feeding bar 14 mounted for movement on top of the feed table B and preferably consisting of an angle plate having a parallel motion toward and from the rotary expanding drum F. This feeding bar preferably consists of an angle plate or iron and its parallel motion may conveniently be derived from a plurality of swinging carrier links 15 arranged in suitable spaced parallel relation and pivotally connected at one end 60 as at 16 to the lower horizontal flange of the

angle plate 14, and at the other end portions pivoted as at 17 to the table top. When the links 15 swing they carry with it the feeding bar 14 but always maintain said bar in parallel relation to the slotted sheet being fed 70 and to the expanding roll which operates upon the slotted sheet. A convenient way of operating the feeding bar is to provide one of the carrier links 15 with a handle extension 18 which may be operated by one 75 hand of the operator.

The sliding feeding bar 14 has fitted thereto and carries therewith a work holding gauge 19 preferably consisting of a sheet steel or equivalent plate and having an inclined web portion 20 formed at its lower edge with a horizontal slide flange 21 which slidably rests upon the table top, and at its upper end formed with an angular bracket portion 22 having a terminal depending attaching flange 23 which is screwed, riveted, or otherwise securely fastened to the vertical flange of the feeding bar 14. At the juncture of the inclined web portion 20 of the plate 19, with its angular bracket portion 22, there is formed an abutment seat or groove 23 in which is seated the back edge of the slotted sheet S when placed in position for feeding to the ribbed or toothed expanding drum.

Another feature of practical importance in the present invention is the mounting of the pressure bar E between the upstanding end frame brackets D of the machine. That is to say, it is the purpose of the present invention to pivotally mount the pressure bar D so that it may be pushed by the operator to an out of the way position as indicated in Fig. 4 when the slotted sheet is inserted thereunder for engagement with the first tooth of the expanding drum. It is then allowed to drop to its vertical position shown in Fig. 1 immediately over the die block C and place a slight frictional holding pressure upon the slotted sheet while not interfering with its longitudinal reciprocations or vibrations as the diagonal strands are pulled to the open position shown in Fig. 9 of the drawings. Any convenient way of pivotally mounting the pressure bar D may be employed but as shown in the drawing a practical way of accomplishing that is to have secured to each end of the pressure bar (as shown in Fig. 5) a pivot plate 22 provided with a pivot stud 23 pivotally engaging a bearing socket 24 provided at the inner side of each of the end frame brackets E. Also above the pressure bar D at each end thereof is mounted a stop plate 25 (see particularly Figs. 5 and 6) against which the top corner of the pressure bar engages when it drops to its vertical position shown in Fig. 1 thereby preventing the pressure bar being drawn out of position toward the expanding drum as the latter rotates and

bends down the slotted sheet over the edge of the stationary die block C.

As already indicated, the improvements herein described are especially adapted to 5 accommodate a herringbone type of slotted metal sheet as shown in Fig. 8 of the drawings, and in order effectually to properly open the meshes of such a sheet the said holding and feeding unit is provided to 10 hold the sheet S at an inclination as shown in Figs. 1 and 2 of the drawings, and also to feed it at that angle, by the operation of the feeding bar 14 and the actuating means therefor, to the teeth of the drum. In Fig. 15 8 of the drawings is shown the pre-slotted sheet S having the usual arrangement of the diagonal slits for the herringbone lath and this sheet is fed in the position shown in Figs. 1 and 2 over the table and the station- 20 ary die block so as to bring the inside edge of the sheet into the land of the expanding drum. At this point it will again be noted that the die ribs are substantially continuous throughout the length of the drum, and 25 the points of every two ribs are spaced apart a distance approximately the distance between the uncut strips or ribs of the herringbone sheet when in its expanded condition.

30 When the sheet is fed between the pressure bar and the die block C it is to be understood that the frictional resistance offered to the feed of the sheet between the said bar and die block is greater than the force exerted 35 to expand or open the sheet, but not sufficient to interfere with a part of the sheet reciprocating longitudinally of the drum to adapt itself to the swing of the strands as they are pulled open to the diagonal position 40 shown in Fig. 8 which they occupy in the herringbone mesh.

From the foregoing it is thought that the construction and advantages of the improvements herein described will be understood 45 without further description and that changes in the form, proportion and minor details of construction may be resorted to without departing from the principle or sacrificing any of the advantages of the invention.

50 I claim:—

1. The herein described method of expanding a pre-slotted metal sheet of the herringbone type which consists in operating a rotary toothed expanding member against the 55 successive uncut strips of the sheet between the slotted sections thereof, and simultaneously causing the sheet to be fed to the expanding member in a manner to permit it to reciprocate or vibrate longitudinally.

60 2. An expanding machine for pre-slotted metal sheets including a frame having a table top and a die member, an expanding drum having substantially continuous longitudinal non-cutting shoulders and arranged 65 to rotate in proximity to such die member

and to engage an uncut part of the sheet parallel to its edge, and a sheet holding and feeding unit arranged to operate over the table top.

3. An expanding machine for pre-slotted 70 metal sheets including a frame having a table top and a die member, an expanding drum having substantially continuous longitudinal non-cutting shoulders and arranged to rotate in proximity to said die 75 member and to engage longitudinal uncut portions of the sheet parallel to its edge, and a sheet holding and feeding unit arranged to operate over the table top and having means for holding the sheet in an inclined 80 position.

4. An expanding machine for pre-slotted 85 metal sheets including a frame having a table top and a stationary die member, an expanding drum having substantially continuous longitudinally disposed non-cutting shoulders arranged to rotate in proximity to said die member, and adapted to engage longitudinal uncut portions of the sheet 90 parallel to its edge, a pivotal pressure bar mounted over the stationary die member, and a sheet holding and feeding unit arranged to operate over the table top at one side of said pressure bar.

5. An expanding machine for pre-slotted 95 metal sheets including a frame having a table top and a stationary die member at one edge thereof, an expanding drum having substantially continuous longitudinally disposed non-cutting shoulders and arranged to rotate in proximity to said stationary die member thereby to engage longitudinal uncut portions of the sheet parallel to its edge, brackets arranged at the ends of the table top 100 and provided with bearings and stop elements, a pressure bar carrying at its ends pivot projections adapted to engage in said bearings, said bar being adapted to engage said stop elements, and a sheet holding and feeding unit operating on the top of the 105 table top at one end of the pressure bar.

6. An expanding machine for pre-slotted 110 metal sheets including a frame having a table top and a stationary die at one edge thereof, a ribbed expanding drum arranged to rotate 115 in proximity to said die, a pressure bar supported over the die, and a sheet holding and feeding unit operating from the table top and comprising a suitably operated sliding feed bar and a work holding gauge carried by said bar and provided with an inclined portion and an abutment seat or groove at the upper part of said inclined portion to receive an edge of the blank being fed and to 120 hold it in an inclined position.

7. An expanding machine for pre-slotted 125 metal sheets including a frame, a table with a die member, a pressure bar located over the die member, a ribbed expanding drum ar- 130 ranged to rotate in proximity to such die

member, and means for feeding a slitted sheet against the expanding drum at right angles to its axis.

8. An expanding machine for pre-slitted metal sheets including a frame, a table with a die member at its edge, a pressure bar located over the die member, a ribbed expanding drum arranged to rotate in proximity to

such die member, and means for feeding a slitted sheet to the expanding drum at right angles to its axis, said means being so arranged as to permit longitudinal reciprocating motion of the sheet.

In testimony whereof I hereunto affix my signature.

JOSEPH A. HALLS.
